EXPANSION JOINT DOWEL HOLDER

Russell R. Robertson, Patterson, Calif., assignor,
by mesne assignments, of one-half to Elfreda
C. Robertson, Patterson, Calif.

Application April 29, 1944, Serial No. 533,382

3 Claims. (Cl. 94—51)

1

This invention relates to a device for holding or locating the dowels, such as used in connection with expansion joint strips, between adjacent slabs of concrete highways or runways, and which are employed to prevent relative vertical displacement of the concrete at said ends of the slabs.

It is necessary to maintain the dowels properly axially aligned and parallel to each other and to the slabs if they are to properly perform their function and avoid cracking of the concrete with the expansion or contraction of the same. This alinement must be done before the concrete is poured and the dowels must be properly held in their alined position in such a manner that they will not be disturbed when the concrete is poured.

At present this is done by placing a chair under each dowel after the same is carefully placed in its proper position. Frequently tie rods are used in addition to the chairs, and in all such operations not only is considerable time consumed, but the chairs and rods become permanently buried in the concrete, and since they cannot be reclaimed the amount of metal they represent is lost.

In view of this condition, it is the principal object of my invention to provide a dowel locating and retaining device by means of which all the dowels in a strip of reinforcing material may be simultaneously positioned and held in properly alined relation with each other in a single, quickly performed operation.

A further object is to provide a device for the purpose which is adapted to be removed from its dowel locating position as soon as the concrete is poured, without danger of shifting the dowels from their set position and with a minimum disturbance of the concrete. The device is therefore capable of repeated use indefinitely and no metal is wasted. Also, the time needed to properly position and set the dowels is reduced to a minimum, and labor and time are conserved.

A further object of the invention is to produce a simple and inexpensive device, and yet one which will be exceedingly effective for the purpose for which it is designed.

These objects I accomplish by means of such structure and relative arrangement of parts as will fully appear by a persual of the following specification and claims.

In the drawing similar characters of reference indicate corresponding parts in the several views:

Figure 1 is a fragmentary top plan view of my improved dowel locating and alining device.

Figure 2 is an enlarged cross section on line 2—2 of Fig. 1.

2

Figure 3 is a fragmentary elevation of the device adjacent one end thereof.

Referring now more particularly to the characters of reference on the drawing, the dowels 1 to 5 be alined are mounted as usual in a strip 2 of suitable expansion material, which is set transversely of the road or runway to be poured, and extends the full distance between the side limit boards or rails 3. The dowels extend through 10 the strip in a common horizontal plane intermediate the top and bottom edges thereof in equally spaced relation throughout the length of the strip, and project substantially equal distances on opposite sides of the strip, as usual.

On one side of the strips the dowels are sheathed in thin sleeves 4 slidably fitted thereon. The sleeves preferably project some distance beyond the outer end of the dowels, as shown in Fig. 2, the projecting portions being filled by a compression or expansion plug 5.

My improved dowel locating and holding device to be used with the above described dowel arrangement and supporting strip comprises a saddle 6 of inverted U-shaped form adapted to 25 movably but somewhat closely fit over the strip 2 and to extend to the level of the bottom of the dowels or slightly below; the sidewalls 7 of the saddle being notched, as at 8, to clear the dowels, as shown in Fig. 3.

Secured on each side wall 7 and projecting 30 outwardly therefrom a distance less than the projecting portion of the dowels are rigid members 9 of substantially U-form in a horizontal plane and rigid with the saddle 6. These members are located above the different dowels and 35 their outer end portions 10, which are substantially parallel to the side walls 7, are centrally notched on their under sides, as at 11, to form saddles fitting over the upper portion of the dowels.

When the device is in place it is supported 40 from the dowels by the notched portions 10, the top of the saddle 6 being then clear of the top of the strip 2, as shown in Fig. 2, so that the entire weight of the device rests on the dowels 45 themselves.

The members 9 are preferably formed of sheet metal set on edge so as to offer a minimum area of resistance to upward movement through the concrete, and they may be formed as a continuous strip from end to end of the device, being then suitably bent to shape, as shown in Fig. 1.

The members 9 may be braced by diagonals 12 extending upwardly from their outer portions 10 to the saddle 6 adjacent the top, and said braces on one side of the saddle may be formed

with extensions 13 having depending fingers 14 adapted to overlap and thus align the adjacent ends of the dowels, as shown in Fig. 2.

The saddle at its ends is provided with opposed horizontally projecting lugs 15 serving as a means for engagement with a pry-up lever or the like when removing the device from place. Also between certain of the members 9 adjacent the level of the bottom edge thereof the device may be provided with horizontal ears 16 orificed for the reception of locating stakes if desired.

In operation, the saddle 6 is first placed over the strip 2, the device coming to rest on the dowels regardless of their initial alinement. Said dowels are then tipped laterally as may be necessary to locate them in the notches 11, and when the dowels are all so located they are in proper alinement both longitudinally and transversely of the road-bed. Also if necessary, and if the fingers 14 are used, the dowels are shifted lengthwise to bring the corresponding ends against the fingers.

The weight of the device on the dowels holds them in such alined positions when the concrete is poured, so that such pouring will not disturb them. After the pouring operation on opposite sides of the strip 2 is complete, the device is pulled straight up, the thin area presented to the concrete with the upward movement of the device preventing any material disturbing of the concrete. Since the notches 11 are the only elements actually engaging with the dowels at any time, the upward movement of the device away from the dowels does not tend to disturb or dislodge the same from their proper alined positions.

From the foregoing description it will be readily seen that I have produced such a device as

substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

15. A device for use in properly locating an expansion joint filler strip and dowels projecting therethrough, which device comprises a unitary structure including a saddle of substantially inverted U-shape to fit over the strip for substantially the length thereof, relatively thin rigid U-shaped elements each having the free ends of the legs thereof secured to a vertical side face of the saddle and such U-shaped element projecting thence horizontally out from said side face of the saddle and the under edge of its closed outer end being provided with a notch adapted to fit over a dowel projecting through the strip, whereby to hold the dowels at substantially right angles to the strip.
20. 2. A device as in claim 1, including a diagonal brace element interposed between and secured to the outer end of each of the U-shaped dowel locating members and the saddle.
25. 3. A device as in claim 1, including finger members of substantially equal length secured to and projecting from the outer ends of the U-shaped dowel locating members on one side of the saddle, such fingers being adapted to engage the ends of the dowels and limit the extent of their projection to that side of the saddle.
